UNITED STATES PATENT OFFICE.

NOTEN D. BALLANTINE, OF OMAHA, NEBRASKA.

FASTENING MEANS FOR DOORS AND OTHER CLOSURES.

Application filed March 9, 1922. Serial No. 542,326.

To all whom it may concern:

Be it known that I, NOTEN D. BALLANTINE, a citizen of the United States, residing at Omaha, in the county of Douglas and 5 State of Nebraska, have invented certain new and useful Improvements in Fastening Means for Doors and Other Closures, of which the following is a specification.

This invention pertains to a device for securing in position, edge upon edge, planks, battens, or sectional doors employed as temporary closures for the doorways of grain cars or box cars employed for carrying loose grain in bulk.

10 In lading cars with loose or unsacked grain, and with other cargoes comprising a great number of small particles or units, it is customary to deliver the same through the doorway or doorways at the midlength of 20 the car and to pile it up to the load line, or as nearly thereto as its angle of repose will permit, until it flows or spreads out to the central portion of the car between the side doorways. When this point is reached, 25 planks, battens, or horizontally divided doors are set up, edge upon edge, against the door posts, the lowermost plank or member resting directly upon the car floor. The planks, battens, or door sections require to be secured 30 to the door posts to prevent their falling down or shifting out of place, and this has heretofore been accomplished by the use of nails, driven through the planks, battens or door elements and into the door posts, and 35 at the bottom, into the car floor.

The use of nails is objectionable because they tend to split the planks or boards, in whatever form used; to injure the door posts; and to render difficult the withdrawal 40 of the nails to release the temporary closure. Often the nails are broken off, leaving a portion protruding, and these frequently cause injury to sacked or to finished commodities, and sometimes to trainmen and freight 45 handlers. The aggregate loss through breakage or injury of the closure elements, damage to cars and commodities, and injury to employees is very considerable.

The device now to be described is designed 50 to obviate the undesirable consequences attending the use of nails, and to simplify the work and lessen the time required in setting up and securing the temporary closures referred to. It is illustrated in two slightly

variant forms in the accompanying drawings, wherein:

Figure 1 is a fragmentary perspective view of a freight car body showing the doorway and one of the door posts or jambs, with two planks or door sections in position and secured by my improved fastening device;

Fig. 2 is a perspective view of the device itself prior to application, a pointed spur being provided near one end to enter the lower edge of the plank or door element 65 above it;

Fig. 3, a similar view, but showing an upstanding lug or extension to engage against the inner face of the plank, batten or door element instead of being driven or forced 70 into its lower edge;

Fig. 4, a transverse vertical sectional view of two planks or door elements placed edge upon edge against a door post, and secured 75 in position by my improved fastener or device;

Figs. 5, 6 and 7, perspective views illustrating the several steps involved in applying the fastener, in the order in which they 80 are performed;

Fig. 8, a perspective view of the device with the upstanding spur or lug omitted, as 85 may be done when the device is intended for use at a point or points intermediate the door posts; and

Figs. 9, 10, 11 and 12, views illustrating the mode of application and use of the device in this form.

Referring first to Fig. 2, which shows the fastener ready for application to either the 90 right or the left hand door jamb, it will be seen to comprise a wire or slender stem 1, both extremities of which are sharpened or pointed to facilitate their being driven or forced respectively into the closure elements 95 and into the door post or jamb. The end which is to enter the door jamb or post is bent at substantially a right angle to the stem 1, to form a spur 2, while the opposite end is given two similar bends at the points 3 and 4 respectively, the portion 5 beyond the bend 3 constituting a spur to enter the inner face of the door element, and the arm or portion 6 between the bends 3 and 4 being 100 made long enough to have an adequate bearing against such inner face of the door element to firmly hold the same. As seen in said Fig. 2, the spur 2 and arm 6 are parallel

one with the other, while the spur 5 is substantially in the same plane with the stem 1, and extends inward beneath and parallel with said stem 1.

5 At a point between the spur 2 and arm 6 the stem 1 is provided with a loop or bend 7 of size sufficient to afford a grip for the fingers, or to receive a rod or small implement by which to twist or apply torsion to 10 the stem 1, so as to swing the spur 2 to a position or angular relation of 90° or thereabout to the arm 6, so that while said arm stands in vertical position to obtain effective hold upon the door or closure element, the 15 spur 2 shall be in horizontal position where it may readily be forced or driven into the door jamb 8 or face of the post. The loop 7 has the further purpose or function of enabling the person applying the device to 20 shorten its length and thereby draw the door elements firmly against the post after the spurs 5 and 2 are successively driven into the said door elements and into the door jamb or post, respectively. This is effected 25 by introducing a rod, hammer, or other suitable implement into loop 7, and winding or twisting the branches or portions of stem 1 on opposite sides of the loop about each other.

30 Projecting upwardly from the stem 1 of the device, close to bend 4, is a spur 9, sharpened to enter the lower edge of a board, batten or door element dropped upon it from a short distance above it, the spur serving to 35 retain such lower edge in place.

In the modified form shown in Fig. 3 the construction differs from that of Fig. 2 merely in that instead of providing a sharpened spur to penetrate the lower edge of the 40 plank or door element, the stem 1 is bent to form an upstanding lug or extension 10 of the bearing portion 6, to lie back of the closure element and hold its lower edge in alignment with that of the element next below, and its outer face snugly against the 45 door post.

In applying the device, the lowermost plank or element 11 of the temporary door or closure is placed on edge upon the ear 50 floor across the doorway or opening, and with its ends lapping over or beyond the side posts of the doorway, as indicated in Fig. 1. One of the fasteners is then laid across the upper edge of the door element, 55 with the point of spur 5 in contact with the inner face of said element or member. A slight tap of a hammer, or application of moderate pressure will force spur 5 into the inner face of the member, bringing the arm 6 into contact with said face, and causing 60 spur 9 or lug 10 to stand in position to enter or to pass behind the lower edge of the next plank or element 12 of the closure, to be dropped edgewise down upon the lowermost 65 element 11. The spur 5 being forced into

the plank or element 11, the spur 2 is bent to the right or left to point toward the left or the right hand jamb, as the case may be, with which it is to engage. The spur 2 is then driven or forced into the door jamb or post, thus firmly anchoring the fastener thereto. Finally, a suitable implement, as a short iron rod, a hammer handle, or other, is inserted into the loop 7, and the crossing portions of the stem 1 are twisted into a spiral 75 or are wound one around the other, thus shortening the stem 1 and drawing spur 5, arm 6, and spur 9 or extension 10 toward the spur 2, and so pressing and firmly holding the door elements in close contact with the 80 door posts.

It is manifestly immaterial whether the upstanding spur 9 or extension 10 be employed, as they perform the same office in 85 essentially the same way.

Where the temporary doors or closures are of relatively light material, or the outward pressure is heavy, it is often desirable to provide against the springing of one plank or door element out of plane or alignment with another above or below, and the same device may be employed for this purpose, without 90 change. I prefer, however, for such use, to omit the spur 9 or lug 10, or in other words, to make the device in the form shown in 95 Figs. 8 to 12, inclusive, and to apply it in the way indicated in said figures, the device in its final form being shown in Fig. 1 at a point intermediate the door posts.

The device in this form is shown in Fig. 8, and is placed in vertical position as in Fig. 9, and spur 5 is forced or driven into the inner face of the door or closure element 11, as seen in said figure. This done, the stem 1 is bent over and laid down upon the upper edge of said door element 11, as shown in Fig. 10. Before or after the succeeding closure element 12 is placed in position above element 11, the stem 1 is twisted with or without the aid of a suitable implement applied to loop 7, so that spur 2 points upward and loop 7 stands below stem 1, as shown in Fig. 11. Finally, the stem 1 is given a right angle bend at the point 13, at the forward and lower edge of member 12, and spur 2 is forced or driven into the outer face of said member as shown in Fig. 12, so that as finally applied the fastener has the form and position shown in Fig. 1 at a point intermediate the door posts.

It will be seen that by this simple device, convenient and inexpensive means is afforded for quickly and firmly securing temporary closures in position, and as readily releasing them.

In practice I find it convenient and expedient to form the fasteners of iron or steel wire, of No. 8 British Wire Gauge or thereabout, and preferably galvanized; but they may be made of any suitable metal or alloy

possessing the requisite degree of malleability. I hence do not restrict myself to the use of wire.

Variations may manifestly be made in the form and proportions of the device without departing from the essence of my invention, which resides in the provision of the body having spurs at opposite ends, positioned or positionable at will to enter the door element and the right or left jamb of the doorway, and to anchor the former to the latter, or to tie together two such closure elements. The loop 7 may in some cases be omitted, though not without impairing the convenience and effectiveness of the device.

Owing to the outward pressure of grain or like cargoes against the temporary doors, it is not necessary that the fasteners be heavy or of great strength, their duty being mainly the retention of the door or closure elements in position during the lading of the car.

The device may be used in other situations where similar closures are required or desirable.

The fastenings above described in no way interfere with the usual car doors, and require no special provision or adaptation of the car to permit their use.

What I claim is:—

1. A fastener for temporary car door closures, consisting of a metallic stem provided at one end with a spur turned backward beneath said stem, and connected therewith by an arm at substantially a right angle to the stem and spur; a spur at the opposite end substantially parallel and in plane with said arm; and a loop intermediate the spurs.

2. A fastener for temporary car door closures, consisting of a metallic stem provided at one end with a spur turned back-

ward beneath the stem, and connected therewith by an arm at substantially a right angle to the stem and spur; a spur at the opposite end substantially parallel and in the same plane with said arm; a loop intermediate the spurs; and an upstanding member to engage and hold in place the lower edge of a door or closure element placed above the fastener.

3. A fastener for securing and holding in place individual planks of a temporary doorway closure for freight cars, said fastener comprising a substantial malleable metallic stem provided at opposite ends with laterally projecting spurs pointed and adapted to be driven into said planks, and with an intermediate loop or eye adapted to receive a tool, whereby the loop may be swung about the axis of the stem and caused to shorten the stem and draw together the parts connected by the fastener.

4. A fastener for temporary doors or closures, comprising a wire stem; a spur at one end of the stem and an arm at the opposite end thereof; a spur at the free end of said arm; and a spur intermediate the ends of the stem, said stem, spurs and arm all lying in a common plane.

5. A fastener for temporary doors or closures, comprising a wire stem; a spur at one end of the stem and an arm at the opposite end thereof; a spur at the free end of said arm; a spur intermediate the ends of the stem; and a loop formed in the stem, to receive an implement by which the stem may be twisted to vary the angular relation of the end spurs and to shorten the stem, said stem, spurs, arm and loop all lying in a common plane.

In testimony whereof I have signed my name to this specification.

NOTEN D. BALLANTINE.
